UNITED STATES PATENT OFFICE.

ROBERT M. SEARLE, OF ROCHESTER, NEW YORK.

COPYHOLDER.

Application filed July 19, 1919. Serial No. 312,001.

To all whom it may concern:

Be it known that I, ROBERT M. SEARLE, a citizen of the United States, and resident of Rochester, in the county of Monroe and 5 State of New York, have invented certain new and useful Improvements in Copyholders, of which the following is a specification.

The present invention relates to copy holders and more particularly to the type in 10 which a line guide and a work support are associated in such a manner that one of them may be moved step by step to present different portions of the work to the line guide, for example: as when the work support is 15 moved vertically relatively to the stationary line guide as in U. S. Patent No. 1,014,646, granted January 16, 1912, to R. B. Griffith.

An object of this invention is to associate with the copy holder a lens which will permit 20 the magnification of the work adjacent the line guide so that small print and writing may be enlarged. Another object of the invention is to provide for the illumination of the work adjacent the line guide without 25 producing a glare in the eyes of the user of the copy holder. A still further object of the invention is to provide in connection with the illuminating means, a light filter which will absorb certain of the rays 30 of the illuminating means to give a light similar to daylight.

To these and other ends, the invention consists of certain parts and combinations of parts, all of which will be hereinafter 35 described, the novel features being pointed out in the appended claims.

In the drawings:

Fig. 1 is a front view of a copy holder embodying the present invention, parts being 40 broken away;

Fig. 2 is a side view of the copy holder;

Fig. 3 is an enlarged fragmentary sectional view on the line 3—3 Fig. 1 showing the illuminating means, the light filter being 45 shown in dotted lines in lowered position;

Fig. 4 is a fragmentary view of the supporting means for the lamp and the line guide;

Fig. 5 is a detail view of one end of the 50 lamp casing and the line guide.

Fig. 6 is a detail view showing the manner in which ventilation is obtained between the lamp casing and the work support when the lamp casing is in abutment with the work 55 support.

This invention may be embodied in any

copy holder where the line guide and a work support are relatively movable for the purpose of causing the line guide to point out the successive line of a piece of work. In 60 the illustrated embodiment there is provided a fixed or stationary frame 1 on which the work supporting member or plate 2 is vertically adjustable. This work supporting plate may be moved step by step through a 65 lever 3 pivoted at 4 and connected to another lever 5 which is pivoted at 6, the lever 5 being connected through a rod 7 with a clutch (not shown) such arrangement being similar to that shown in the patent to Griffith No. 70 1,014,646 and being designed to elevate the work support 2 upon the frame 1 step by step as the lever 3 is depressed. The work holder carries at its upper end a work clamp 8 for securing the work to the work support 75 2, the work clamp not forming any part of the present invention.

Associated with the work support is a line guide 9, this line guide being in this instance in the form of a sheet metal plate secured by rolled portions 10 to a bar 11 which lies horizontally in front of the work supporting plate 2. The bar has at each end an arm 12, said arms being pivotally connected at 13 to the stationary frame 1. The 80 bar may be raised and lowered with reference to the plate 2 and at the same time moves toward and from the plate so as to accommodate work of different thicknesses.

Arranged above the bar 11 and parallel 90 therewith is a horizontal bar 14 which has at opposite ends, arms 15 pivotally connected at 13 to the supporting frame 1. Between the bars 11 and 14 a lens 16 may be arranged. This lens is preferably in the form of an 95 elongated bar having its rear face plane and its front face convex or cylindrically formed. This lens bar may be supported at opposite ends by clamps, each of which consists in this instance of a flat plate 17 and a curved 100 plate 18 having curved portions 19 at opposite ends engaging the bars 11 and 14. Screws 20 secure the plates 17 and 18 together and clamp the lens bar 16. The clamps engage the bars 11 and 14 in such a 105 manner as to permit the bars to rock in the clamps as the arms 12 and 15 swing. The line guide 9 projects upwardly below the lower edge of the lens bar and in rear of the latter so that the line guide is visible 110 through the lens. It is apparent that the supporting means for the line guide and the

lens not only permits the line guide to be adjusted to the proper position for the eyes of the user of the copy holder, but the lens itself may be so adjusted that it will correspond to the eyes of the user to give the proper magnification of the work directly above the line guide.

There may also be associated with the copy holder an illuminating means. This means in this instance is in the form of an elongated lamp 21 which is preferably enclosed within a lamp casing or housing 22 of elongated construction lying below the lens and preferably opening upward in rear of the line guide as at 23. The edge of the lamp casing may be corrugated or serrated at 22^a so that when the casing contacts with the work, ventilating passages will be provided to prevent the burning of the work. Furthermore, the casing may be provided with openings 22^b also for the purpose of ventilation.

The line guide in this instance forms a continuation of one edge of the lamp casing and acts to prevent any rays from the lamp from issuing below the edge of the line guide.

There may be used in connection with the illuminating means a light filter preferably in the form of a transparent sheet 24 colored to absorb certain of the rays on the work so that artificial daylight is produced. This sheet of material may be surrounded by a frame 25 which is pivoted at 26 to the lamp casing thus permitting the light filter to be moved to and from a position in front of the lens bar 16.

From the foregoing it will be seen that there has been provided in connection with a copy holder in which the line guide and the work support are relatively movable, a lens for magnifying the work adjacent the line guide, the latter preferably having its guiding edge visible through the lens. The lens is of elongated form and may be moved toward and from the plane of the work so that the lens may be adapted to the eye of the user. Also associated with the copy holder is an illuminating means which directs the illumination upon the work adjacent the line guide, the line guide preferably forming a continuation of the casing which incloses the illuminating means. There is also provided a light filter which may be moved to and from a position where the illuminated work may be visible through the filter, this filter modifying the light rays to produce artificial daylight.

Certain features which may be used in any construction in which there is provided a field to be viewed are not herein claimed broadly but form the subject matter of a divisional application on reading appliances filed by me on June 30, 1921, Serial No. 65 481,633.

What I claim as my invention and desire to secure by Letters Patent is:

1. In a copy holder, the combination with a stationary frame a work support vertically movable on the frame, and a line guide supported by the stationary frame to permit the work support to move relatively thereto, of an elongated lamp arranged parallel with the line guide, and an elongated lamp casing enclosing the lamp and having an opening to throw the light between the line guide and the work support, said casing being so formed that direct rays from the lamp will not pass to the eyes of the viewer of the work on the work support. 75

2. In a copy holder, the combination with a fixed frame, and a work holder vertically movable on the frame, of an elongated lens, two horizontal bars by which said lens is carried, and arms at the ends of each of said bars pivotally connected to the stationary frame and permitting the elongated lens to move toward and from the plane of the work on the work support. 85

3. In combination with a work support 90 and a line guide, one of which is movable relatively to the other, of an illuminating means arranged below said line guide, and an elongated casing inclosing said illuminating means so that direct rays from the illuminating means will not pass to the eyes of the viewer of the work on the work support and opening at its top at a point between the line guide and the work support to direct the rays upon the work. 95

4. In a copy holder, the combination with a work support and a line guide, one of which is movable relatively to the other, of illuminating means arranged below the line guide, and an inclosing casing for the illuminating means opening between the line guide and the work support, the line guide forming a continuation of the inclosing casing at one side of said opening. 100

5. In a copy holder, the combination with a stationary frame, and a work support vertically movable on the frame, of an elongated lamp casing supported from said frame and opening upwardly, the line guide being a continuation of the lamp casing at 115 one side of said opening.

6. In a copy holder, the combination with a stationary frame a work holder movable vertically on the frame and an elongated lens arranged in front of said work holder, of an elongated lamp casing supported by the stationary frame in front of the work holder and opening to direct rays upon the work on the work holder and in rear of the lens. 120

7. In a copy holder, the combination with a stationary frame and a work holder vertically movable thereon, of an elongated lens for magnifying the work on the work holder supported by said stationary frame, a lamp and an elongated lamp casing supported by 125 130

said stationary frame enclosing said lamp so that direct rays from the lamp will not pass to the eyes of a viewer of the work on the work holder and opening in a direction 5 to direct rays between the elongated lens and the work holder.

8. In a copy holder, the combination with a stationary frame, a work support vertically movable on the frame, and a line 10 guide supported by the stationary frame, an elongated lamp arranged parallel with the line guide, of an elongated lamp casing enclosing the lamp so that direct rays from the lamp will not pass to the eyes of the 15 viewer of the work on the work support arranged to direct rays from the lamp on the work directly above the line guide.

9. In a copy holder, the combination with a stationary frame, a work support vertically 20 movable on the frame, and a line guide supported by the stationary frame, of an elongated lamp casing arranged to direct rays on the work directly above the line guide, and a light filter arranged to absorb 25 certain of the rays on the work directly above the line guide.

10. In a copy holder, the combination with a stationary frame, a work support vertically movable on the frame, and a line guide supported by the frame to permit the work 30 support to move relatively to such guide, of an elongated lens supported by the stationary frame to magnify the work directly above the line guide, an elongated lamp casing opening between the line guide and 35 the work support to illuminate the work in rear of the lens above the line guide.

11. In a copy holder, the combination with a stationary frame, a work support vertically 40 movable on the frame, and a line guide supported by the frame to permit the work support to move relatively to such guide, of an elongated lens supported by the stationary frame to magnify the work directly 45 above the line guide, an elongated lamp casing opening between the line guide and the work support to illuminate the work in rear of the lens above the line guide, and a light filter movably mounted in front of the lens.

ROBERT M. SEARLE.
